UNITED STATES PATENT OFFICE.

JOHN J. CROFT, OF ATLANTA, GEORGIA, ASSIGNOR TO CAPITAL CITY CHAIR COMPANY, OF ATLANTA, GEORGIA, A CORPORATION OF GEORGIA.

DAVENPORT BED.

Application filed March 12, 1924. Serial No. 698,772.

To all whom it may concern:

Be it known that I, JOHN J. CROFT, a citizen of the United States, residing at Atlanta, in the county of Fulton and State of Georgia, have invented certain new and useful Improvements in Davenport Beds, of which the following is a specification.

This invention relates to davenports and more particularly to such a device of the 10 "walk-over" type.

An important object of the invention is to provide a device of the above mentioned character which, in folded position, presents an attractive divan, the operating 15 mechanism by which the device is unfolded being entirely hidden from view.

A further object of the invention is to provide such a device having a simplified form of operating mechanism which is efficient in operation and yet inexpensive to manufacture.

A still further object is to provide a davenport having a movable section, which in folded position, is arranged within the 25 davenport frame and covered by a divided cushion to form a divan, the movable section being adapted to be swung outwardly from the davenport frame and the cushions arranged within the frame to form a continuation of the movable section to form a bed.

Other objects and advantages of the invention will be apparent during the course of the following description.

35 In the drawings, I have shown one embodiment of the invention. In this showing,

Figure 1 is a front elevation of the davenport in folded position,

Figure 2 is a perspective view of the davenport partly opened,

Figure 3 is a similar view showing the davenport entirely open,

Figure 4 is a section taken on line 4-4 of Figure 1,

45 Figure 5 is a section taken on line 5-5 of Figure 4,

Figure 6 is a similar view on line 6-6 of Figure 1, and,

Figure 7 is a fragmentary perspective of 50 the connecting bar and associated elements.

Referring to the drawings the numeral 10 designates a davenport frame as a whole embodying a back 11 and ends 12. The lower portion of the frame is provided with 55 a front board 13 connected between the ends

as clearly shown. The davenport frame is adapted to be supported upon suitable legs 14.

The numeral 15 designates a movable section as a whole comprising a skeleton frame 60 16 preferably covered with suitable fabric 17. The section 15 may be provided with box springs 18 of the usual type. The section 15 is provided substantially centrally of its forward edge with a strap or other 65 suitable handle 15'. The section 15 is provided at opposite ends with legs 19 arranged near the front of the section 15 as clearly shown. The legs 19 are preferably secured to the skeleton frame 16 by screws or the 70 like 20 as shown in Figure 6. A link 21 is arranged at each end of the section 15 and one end of each of the links 21 is secured to the skeleton frame 16 intermediate the 75 ends thereof as at 22. The opposite ends of the links 21 are pivotally connected as at 23 with the ends of the davenport frame. As shown in Figure 4 the links 21 normally assume a substantially horizontal position when the device is in folded position. A link 24 is also provided at each end of the section 15 as shown in Figures 4 and 6. These links normally assume an angular position when the device is in folded position as shown in Figure 4 and the upper end of 80 each of the links is pivotally connected as at 25 with the ends of the skeleton frame 16 near the rear edges of the movable section 15. The numeral 26 designates a connecting 85 bar pivotally connected with the ends 12 of the davenport frame by means of supporting members 27. As shown in Figures 4 and 6 the ends of the bar 26 are arranged near the bottom of the davenport ends intermediate the front and rear edges thereof. 90 The lower ends of the links 24 are turned about and secured to the bar 26 as at 28. A spring 29 of the tension type is connected as at 30 to each of the links 24 at points slightly spaced from the bar 26. The rear 100 ends of the springs 29 are secured as at 31 to links 32 which are pivotally connected as at 33 to the davenport ends 12. As will be apparent from Figure 4 the springs 29 exert no tension on the links 24 when the 105 device is in folded position, the lower ends of the links 32 and the rear ends of the springs 29 dropping to the position shown in Figure 4 by gravity.

The numeral 34 designates a link spring 110

carried by a frame 35 which is normally arranged directly below the movable section 15 when the latter is in folded position. The frame 35 may be pivotally connected as at 36 with the back 11 of the davenport frame through brackets 37. The forward end of the frame 35 is supported upon a longitudinal rail 38 carried by the front board 13. A board 39 is arranged between the front board 13 and the back 11 of the davenport frame and the board 39 and section 15 are slightly spaced from the ends 12 of the davenport frame as shown in Figure 5 to provide free movement for the links 21 and 24 and the legs 19.

15 The numeral 40 designates a divided cushion as clearly shown in Figures 1 and 3. While I have shown the cushion divided into three parts it will be obvious that I may 20 use a single cushion or divide it into any desired number of parts. The cushion 40 is of substantially the same width and length as the movable section 15 and when the device is in folded position the cushion 25 is arranged upon the movable section 15 to form a divan seat as will be obvious.

The operation of the device is as follows:

When the davenport is in use as a divan the parts will be in the position shown in 30 Figures 1, 4 and 5. When it is desired to open the davenport to serve as a bed the cushion sections 40 are removed and the section 15 is swung upwardly by grasping the handle 15'. In the position shown in 35 Figure 4 it will be noted that the legs 19 are arranged inwardly of the front board 13 and entirely hidden from view. It will be obvious that a substantial elevation of the forward end of the section 15 is necessary 40 in order to permit the legs 19 to swing over the front board 13. As shown in Figure 4 the links 21 normally assume a horizontal position while the links 24 are arranged angularly. Thus it will be seen that initial 45 movement of the section 15 causes the forward end to move directly vertically while the rear end of the section moves forwardly and upwardly at an angle. Since the links 21 are connected intermediate the ends of 50 the section 15 it will be apparent that the forward end of the section 15 will rise even more rapidly than the central portions so that the legs 19 will clear the front board 13 as shown in dotted lines in Figure 6. 55 After the section 15 has moved a substantial distance the slack in the spring connections 29 and 32 will be taken up and the springs will be tensioned as will be obvious. When the links 21 assume a vertical position it 60 will be obvious that the links 24 are still moving toward the vertical position so that when this point is passed the legs 19 will start to move downwardly, while the rear end of the section 15 will start to move 65 downwardly as soon as the links 24 have

passed a vertical position. This movement is continued until the section 15 assumes the position shown in Figures 3 and 6. The cushion sections 40 are then placed in position on the link spring 34 as shown in Figures 3 and 6. The device is now ready for use as a bed. It will be obvious that the cushion sections 40 form continuations of the movable section 15 when the device is in open position. When it is desired to close 70 the davenport the cushion sections 40 are removed and the movable section 15 is swung upwardly and inwardly by grasping the handle 15'. Since the springs 29 have been tensioned by outward movement of the section 15 it will be obvious that they will assist the inward movement of the section 15 when the bed is being moved to closed position. After the section 15 has assumed the position shown in Figures 1 and 4 the 80 cushion sections 40 may be replaced as will be obvious. The space between the frame 35 and board 39 may be employed as a bedding box by swinging the forward end of the frame 35 upwardly about its 90 pivots 36.

It will be obvious that the operating mechanism for the device occupies but little space between the section 15 and the ends 12 of the davenport frame and all the mechanism 95 including the legs 19 is entirely hidden from view when the device is folded. By securing the lower ends of the links 24 to the bar 26 uniform action of the ends of the section 15 is assured.

100 It is to be understood that the form of my invention herewith shown and described is to be taken as a preferred example of the same and that various changes in the shape, size, and arrangement of parts may be resorted to without departing from the spirit of the invention or the scope of the subjoined claims.

Having described my invention, I claim:

1. A device of the character described 110 comprising a davenport frame embodying a back, ends and a front board, a movable section normally positioned on said davenport frame, a leg carried by each end of said movable section adjacent the front thereof and normally arranged rearwardly of said front board, a link pivotally connected at one end to each end of said movable section intermediate the front and rear edges thereof, said links being normally 115 substantially horizontal and pivotally connected at their opposite ends to the ends of said davenport frame near the front thereof, and a second link pivotally connected at one end to each end of said movable section near 120 the rear edge thereof, the opposite ends of said second named links normally extending forwardly and downwardly and being pivotally connected to the ends of said davenport frame. 125

2. A device of the character described comprising a davenport frame including a front board, a movable section normally arranged on said frame and adapted to be moved to an open position with its rear edge arranged adjacent the upper edge of said front board, legs carried by the forward portion of said movable section and normally arranged rearwardly of said front board, means for causing the rear portion of said movable section to move forwardly and upwardly during the initial movement of said movable section toward open position, and means for causing the forward portion of said movable section to move upwardly substantially vertically during said initial movement.

3. A device of the character described comprising a davenport frame including a front board, a movable section normally positioned on said davenport frame and

adapted to be moved to an open position with its rear edge arranged adjacent the upper edge of said front board, fixed legs carried by said movable section adjacent its forward edge and normally arranged rearwardly of said front board, link means connected between said davenport frame and the rear portion of said movable section, and link means connected between said davenport frame and the forward portion of said movable section, each of said link means extending forwardly from its connection with said movable section, said first named link means extending downwardly at a greater angle than said last named means. 25 30 35

In testimony whereof I affix my signature in presence of two witnesses.

JOHN J. CROFT.
